(57) **CLAIM**

We claim the ornamental design for a stocking cap for fitting over a baseball-type cap, substantially as shown and described.

DESCRIPTION

FIG. 1 is a front elevation view of the stocking cap over a baseball type cap.

FIG. 2 is a rear elevation view of the stocking cap over a baseball type cap.

FIG. 3 is a left side elevation view of the stocking cap over a baseball style cap.

FIG. 4 is a right side elevation view of the stocking cap over a baseball type cap.

FIG. 5 is a top plan view of the stocking cap over a baseball type cap.

FIG. 6 is a side perspective view of the hat in a relaxed condition; and,

FIG. 7 is a bottom perspective view of the hat in a relaxed condition, showing into its interior.

The broken lines shown in the drawings illustrate features of the article to which the design is applied or in which the design is embodied that form no part of the claim.
